(57) **CLAIM**

The ornamental design for a charger for electronic devices, as shown and described.

DESCRIPTION

FIG. 1 is a front, top, and left side perspective view of a charger for electronic devices showing our new design;

FIG. 2 is a front, bottom and right side perspective view thereof, rotated 180 degrees;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof;

FIG. 8 is a rear elevational view thereof, rotated 180 degrees;

FIG. 9 is a front, top and left perspective view thereof, shown in a first environment of use;

FIG. 10 is a front, bottom and right perspective view thereof, rotated 180 degrees, and shown in a second environment of use;

FIG. 11 is a front, top and left perspective view thereof, shown in a third environment of use; and,

FIG. 12 is a front, bottom and right perspective view thereof, rotated 180 degrees, and shown in a fourth environment of use.

The broken lines in the drawings are for the purpose of illustrating portions of the wireless charger and environment that form no part of the claimed design.
